US0D1060900S

(12) **United States Design Patent** (10) **Patent No.:** **US D1,060,900 S**
(45) **Date of Patent:** **** Feb. 4, 2025**

(54) **MANICURE DUST COLLECTOR ASSEMBLY**

(71) Applicant: **Glam and Glits Nail Design, Inc.,**
Bakersfield, CA (US)

(72) Inventors: **Ana Katrina Tan**, Bakersfield, CA
(US); **Khoa Duong**, Bakersfield, CA
(US); **Howard Yip**, Guandong (CN)

(73) Assignee: **Glam and Glits Nail Design, Inc.,**
Bakersfield, CA (US)

(**) Term: **15 Years**

(21) Appl. No.: **29/886,333**

(22) Filed: **Mar. 7, 2023**

(51) **LOC (15) Cl.** **07-05**

(52) **U.S. Cl.** **D32/35**
USPC **D32/15**

(58) **Field of Classification Search**

USPC D28/54.1, 56, 57, 59, 61, 62; D32/15,
D32/17, 18, 21, 35
CPC A47L 7/0052; A47L 7/0066; A47L 7/0071

(57) **CLAIM**

The ornamental design for a manicure dust collector assembly as shown and described.

DESCRIPTION

FIG. 1 is a front perspective view of a manicure dust collector assembly, showing my new design; FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a front perspective assembly view of the manicure dust collector assembly of FIG. 1.

The broken lines in the drawings depict portions of the manicure dust collector assembly that form no part of the claimed design.

1 Claim, 8 Drawing Sheets
